UNITED STATES PATENT OFFICE.

JAMES LOCHER, OF DECATUR, ILLINOIS.

CAR-COUPING.

SPECIFICATION forming part of Letters Patent No. 349,805, dated September 28, 1886.

Application filed July 31, 1886. Serial No. 209,620. (No model.)

To all whom it may concern:

Be it known that I, JAMES LOCHER, of the city of Decatur, county of Macon, and State of Illinois, have invented certain new and useful Improvements in Car-Couplers, of which the following is a specification.

My invention relates to car-couplers in which the draw-bars are connected by links and pins; and it consists in certain details of construction and combinations of parts, as hereinafter set forth and claimed, whereby the operation of coupling may be automatic.

In the drawings accompanying and forming a part of this specification, Figure 1 is a central vertical section of opposing draw-bars constructed and coupled in accordance with my invention. Fig. 2 is a central vertical section of said draw-bars separate, and having the various parts properly adjusted preparatory to making a coupling automatically. Fig. 3 is a central vertical section of a draw-bar. Fig. 4 is a horizontal section of the draw-bar shown in Fig. 3, on dotted line *x*; and Fig. 5 is a central vertical section of a draw-bar illustrating a modification of my invention.

a represents the draw-bar, having longitudinal recess *a'*, link-guiding incline *a''*, vertical aperture *g g'*, slot *d*, and groove *e*.
b is a coupling-pin having enlarged head *b'* and conoidal point *b''*.

c, c', c'', and c''', collectively, represent a trip-lever for the coupling-pin, *c* being a vertical bar extending through slot *d* into groove *e*, *c'* being a horizontal upper extension of bar *c*, *c''* being a lower horizontal extension of bar *c*, and *c'''* being an aperture in portion *c'* of a size to freely admit pin *b*. The pin and link are essentially the same as those commonly used in ordinary hand-couplers, and the draw-bar may be attached to the car in any well-known manner. The trip-lever has a limited amount of free vertical motion in groove *e*, and a limited amount of free pivotal motion in slot *d*.
Groove *e* lies to the rear of recess *a'*, and when the bar *c* is in a vertical position in said groove there is nothing to oppose the insertion of the link to the extreme depth of the recess.

In preparing to make a coupling a trip-

lever and pin are raised to the position shown at the left of Fig. 2, the end of the link is placed under horizontal termination *c''* of the trip-lever, and the weight of the trip-lever and pin is utilized to hold the link in a horizontal position. In the opposing draw-bar with which the coupling is to be made the pin and trip-lever are placed in the position shown at the right of Fig. 2, the lower portion of the trip-lever extending diagonally across the inner end of the recess of the draw-bar. When the cars are moved together, the draw-bars come in contact one with the other, and the projecting end of the link strikes the lower end of the trip-lever in the opposite draw-bar, carrying said trip-lever into the position shown in Fig. 1, and causing the pin to fall and engage the link. Then, as the draw-bars separate, through reaction or tension, the link is drawn from under termination *c''*, and the pin and trip-lever fall, leaving all the parts in the positions shown in Fig. 1.

The uncoupling is effected by withdrawing a pin by hand, in the customary manner, and, if desired, a coupling may at any time be made by hand. As the trip-lever is thrown by the link, it carries the pin into a vertical position, and, with the assistance of the conoidal points *b''*, guides said pin through the link and into lower aperture, *g'*.

In Fig. 2, the pin to the right is supported solely by friction, but in the modification set forth in Fig. 5 an upward extension of the trip-lever fits under the head of the pin, furnishing a positive support therefor. In both cases the link operates the trip-lever, causing the pin to fall, and either form may be used with good results.

Having thus described my invention, I claim as new and desire to secure by Letters Patent—

In car-couplers, the combination of draw-bar *a*, having recess *a'*, vertical aperture *g g'*, slot *d*, and groove *e*, trip-lever *c c' c'' c'''*, pin *b*, and link *f*, all constructed and arranged to operate as and for the purpose set forth.

JAMES LOCHER.
